Primary Examiner — Derrick Holland*Assistant Examiner* — Janice Lim(74) *Attorney, Agent, or Firm* — St. Onge Steward Johnston & Reens, LLC**CLAIM**

The ornamental design for an anti-insect applicator, as shown and described.

DESCRIPTIONFIG. 1 is a front isometric view of an anti-insect applicator, showing my new design; and,
FIG. 2 is a front isometric view thereof, shown with the cap removed.

The broken line portions of FIGS. 1 and 2 are included to show unclaimed subject matter only and form no part of the claimed design.

1 Claim, 2 Drawing Sheets*FIG. 1*

FIG. 2
